UNITED STATES PATENT OFFICE

2,535,709

SEAR MECHANISM

Walter R. Weeks, Hamden, Conn., assignor to
General Electric Company, a corporation of
New York

Application September 26, 1946, Serial No. 699,399

2 Claims. (Cl. 42—69)

1

My invention relates to a sear mechanism, more particularly to a sear mechanism for automatic guns, and has for its object simple and reliable means for positively latching and securing the bolt of the gun while, at the same time, providing for the release of the bolt with a minimum force for the firing of the gun.

My invention has particular application to a gun in which the bolt is retained in a gun-unloaded or "Out of Battery" position until the gun is to be fired at which time the sear mechanism is operated to release the bolt.

It will be understood that in automatic guns, especially machine guns of substantial size, the bolt of the gun is thrown back upon the firing of the gun with a tremendous force and the bolt, after striking the recoil or buffer spring, is moved forward with a tremendous force.

In accordance with my invention, in one form I provide a pivoted latching arm having a latching roller on one end and having its other end mounted on a pivot pin which is movable against the force of a spring so that when the roller is engaged by the gun bolt the roller arm and pivot pin are moved against the spring force for a predetermined distance. I have also provided a latching stop for the latching arm for preventing movement of the arm to a released position, this stop being engaged by the roller after the roller has been moved a slight distance by the gun bolt.

For a more complete understanding of my invention reference should be made to the drawing, Fig. 1 of which is a fragmentary view, partly in section, of sear mechanism embodying my invention; Fig. 2 is a fragmentary plan view of Fig. 1; Fig. 3 is a view similar to Fig. 1 but showing the sear mechanism in the bolt-released position, while Fig. 4 is a view similar to Fig. 1 but showing the position of the parts of the sear mechanism at the instant the bolt is stopped by the sear mechanism.

Referring to the drawing, I have shown my invention in one form as applied to the latching and securing the gun bolt 1 mounted for rectilinear movement in a predetermined path from the left hand, as viewed in Fig. 1, toward the right hand and vice versa. When the gun is fired it will be understood that the bolt 1 is thrown by the force of the explosion toward the left hand to an extreme position into engagement with a recoil or buffer spring (not shown) from which it rebounds and moves toward the right hand a short distance and is secured in the gun-unloaded position shown in Fig. 1 by the sear mechanism 2. When the gun is to be fired the sear mechanism

2

is operated to release the bolt whereupon the bolt is moved by a suitable spring (not shown) in a right hand direction to the loading position, the gun breach mechanism is locked in place, and the gun fired.

In accordance with my invention the sear mechanism 2 comprises a latching roller 3 mounted on a U-shaped arm or frame 4 provided with a pivot pin 5. The arm 4 and the roller 3 are biased about the pivot pin 5 in a clockwise direction to a bolt latching position by a spring 6 until a projection 7 on the arm 4 engages a stop pin 8, as shown in Fig. 1. In this position the roller 3 engages a projection 9 on the bolt 1, thereby latching and holding the bolt in its gun-unloaded position as shown. In order to release the bolt, the arm 4 is turned counterclockwise by means of a link member 10 having an elongated aperture 11 into which projects a pin 12 on the arm 4. When the gun is to be fired the link 10 is moved toward the left hand, thereby to turn the arm 4 counterclockwise against the force of the spring 6 to the position shown in Fig. 3, whereby the bolt is released.

For the purpose of normally positioning the pin 5 as well as the roller 3 and arm 4 in one extreme position as shown in Fig. 1, I provide a heavy helical spring 13 of suitable strength which is mounted in a bore 14 in a metal block member 15. The block 15 is secured rigidly to the frame 16 of the gun by means of two screws 17. Moreover, the block 15 is provided with an arcuate concave surface 18 extending parallel with the roller 3 having substantially the same curvature as the surface of the roller, and with an aperture 19 for the pivot pin 5 having a diameter considerably greater than the diameter of the pin, about fifty percent greater as shown in the drawing. Normally, the pin 5 is biased toward the left hand by the spring 13 along a path substantially parallel with the path of movement of the bolt 1 against the left hand wall of the aperture 19, the right hand end of the spring bearing against the stop member 20 on the block 15 and its left end being provided with a plunger-shaped member having a shank 21 fitting inside the spring 13 and an outer head 22 slidably fitting in the bore 14. In the head 22 is a semi-circular groove 23 extending diametrically across its face into which fits the pin 5.

When the bolt 1 is thrown toward the left hand upon firing of the gun its projection 9 moves past the roller 3 depressing the roller and thereupon the roller is moved back to engaging position by the spring 6 so as to secure the bolt when

it moves back again after engaging the buffer spring of the gun. The bolt is thrown from the buffer spring toward the right hand at a very high speed and strikes the roller 3 with a tremendous force, pushing the roller 3, the arm or frame 4, and the pin 5 toward the right hand against the force of the spring 13 until finally the roller is stopped by abutting engagement with the curved surface 18. After the bolt has thus been stopped the spring 13 moves the pin 5 toward the left hand, and with it the arm 4, roller 3, and the bolt 1 to the positions shown in Fig. 1. In this position the roller 3 may be moved to release the bolt by the firing member 10.

An important feature of my invention is the positioning of the curved surface 18 so as to catch the roller 3 and prevent downward movement of the roller after the roller has been moved toward the right hand a very short distance, at which time the lower side of the roller strikes the lower lefthand edge or projection 24 of the surface 18. Therefore, the surface 18 acts as a positive stop to prevent downward movement of the roller and thereby makes possible the use of a comparatively weak biasing spring 6 whereby a correspondingly small force is required to move the roller 3 downward in the release of the bolt. The spring 6 need be strong enough only to turn upward the arm 4 and roller 3 to the latching position of Fig. 1 in time to catch the bolt as it moves back toward the right hand after engaging the buffer spring. The spring 13, while yielding to provide for engagement of the roller 3 with the surface 18, is strong enough to assure the normal positioning of the parts as shown in Fig. 1.

While I have shown a particular embodiment of my invention, it will be understood, of course, that I do not wish to be limited thereto since many modifications may be made and I therefore contemplate by the appended claims to cover any such modifications as fall within the true spirit and scope of my invention.

What I claim as new and desire to secure by Letters Patent of the United States is:

1. Latch mechanism comprising an arm, a pivot for one end of said arm, a latching roller on the opposite movable end of said arm, supporting means for said pivot arranged to provide for limited movement of said pivot in a predetermined path, a first spring for normally biasing said pivot, arm, and roller in a predetermined direction along said path to predetermined positions, a second spring for biasing said arm and roller about said pivot to a predetermined latching position, means for turning said arm about said pivot

against the force of said second spring to a released position, and a rigid stop member for said roller normally spaced from said roller to provide for movement of said roller about said pivot to said released position when said pivot is in its said predetermined position, said stop member being provided with a concave surface in position to be abuttingly engaged by said roller and bring said latching member to rest when said roller is moved a predetermined distance along said predetermined path against the force of said first spring.

2. Sear mechanism for securing a gun bolt movable in a predetermined path comprising an arm, a pivot for one end of said arm, a bolt latching roller on the opposite movable end of said arm, supporting means for said pivot arranged to provide for limited movement of said pivot in a path substantially parallel with said predetermined path, a first spring for normally biasing said pivot, arm, and roller in a predetermined direction along its said path to predetermined positions, a second spring for biasing said arm and roller about said pivot to a predetermined latching position, means for turning said arm about said pivot against the force of said second spring to a released position, a rigid stop member for said roller normally spaced from said roller to provide for movement of said roller about said pivot to said released position when said pivot is in its said predetermined position, said stop member being provided with a concave surface abuttingly engaged by said roller to bring said roller to rest when said roller is moved by the gun bolt a predetermined distance along said predetermined path against the force of said first spring, and a projection on said stop member forming a continuation of said concave surface extending toward said latching member on the side of said roller toward which said roller moves to said released position and engaged by said roller thereby to prevent movement of said roller about said pivot from said latching position.
